NICHOLAS M. GOODLETT, OF NEW YORK, N. Y., ASSIGNOR TO ARKELL SAFETY BAG COMPANY, OF NEW YORK, N. Y., A CORPORATION OF NEW YORK.

PROCESS AND MECHANISM FOR MAKING CRINKLED PAPER.

Application filed December 19, 1918. Serial No. 267,430.

This invention relates to a new and improved process and mechanism for making crinkled paper and consists in the steps and features hereinafter set forth.

5   Heretofore in crinkling paper by the use of a crinkling cylinder and a doctor, the necessary adherence of the paper to the crinkling cylinder has been attained by smoothing the paper while wet against the
10   crinkling cylinder at a point on the cylinder remote from the doctor. In the region of the doctor and particularly at or immediately in advance of the operating edge of the doctor, there was nothing to press or
15   hold the paper on the cylinder and cause it to resist the stripping action of the doctor. The slight adhesion of the wet paper to the cylinder is all that was relied upon to enable the doctor to do its work. As a result,
20   in the heavier and stiffer grades of paper there has been a lack of fineness and closeness in the crinkles. It has also been found in practice that this slight adhesion of the wet paper to the cylinder is not always
25   uniform throughout the width of the paper nor for papers of different grades and characteristics. There has been found a tendency for the paper to scale off in uncrinkled spots under certain conditions and
30   particularly along the margins thereof. This is especially true in papers adapted and designed for wrapping and packing purposes. In papers of this character, it has generally been found necessary to saturate the paper in order to make it adhere to the crinkling cylinder to such a degree as would enable the doctor to perform its function. For this purpose it has been the practice to pass the paper through a vat or vats of water which, in some cases, had to be kept at a high temperature. This copious use of water acted to weaken the paper by dissolving the sizing and unfeathering, to a certain degree, the fibres of the paper. Paper crinkled in this way is quite wet after it passes from the doctor and to extract the moisture the paper must pass through an elaborate drying unit that is expensive to build and to operate.
45   Furthermore, in the processes and machines heretofore in use for crinkling paper, there has been no reliable way of regulating the degree of adherence of the paper to the crinkling cylinder. It was simply smoothed on the cylinder by a roll remote from the doctor and left to adhere by the moisture imparted to the paper. In making crinkled paper for packing and wrapping purposes, the chief advantage of the crinkles in the paper is that they render the paper stretchable so that when the paper is put under strain, it stretches rather than breaks. The degree of stretchability required in the finished paper varies in accordance with the particular use to which the paper is to be put and, for reasons of economy, it is therefore important that some way be provided for regulating the amount of stretchability in the paper so that the customer requiring, say, thirty per cent of stretchability in the paper will not be required to take paper having fifty per cent of stretchability at a price that is higher because of the greater quantity of paper involved. Heretofore, the only feasible way of regulating the stretch in the crinkled paper has been to stretch the crinkled paper while it is moist to reduce the crinkles and thereby reduce, and to that extent regulate, the stretchability of the final product. There was no reliable way of regulating the fineness, closeness or number of crinkles as the same were produced by the doctor and therefore no reliable way of regulating the stretchability in the completed product, except by stretching, as stated.
55   I have discovered a new method of causing the paper to adhere to or remain on the crinkling cylinder to resist the stripping action of the doctor, abutment or other crinkle forming means in forming the crinkles, whereby the use of water or other adhesive agent applied to the paper to enable it to adhere to the crinkling cylinder may be avoided. In this new method, the paper is held on the crinkling cylinder, or other supporting surface for the paper, by pressure and particularly by fluid pressure. Many new results and advantages thus arise in the crinkling of paper. In the first place, water being unnecessary in this new method to enable the paper to adhere to the crinkling cylinder or support, a drier to eliminate water from the crinkled paper is not needed. This effects a great economy in coal consumption heretofore necessary to operate the drier. It also assures a more comfortable and healthful room temperature for the
60

95
100
105

operators. It also saves much or all the space heretofore occupied by the drier which generally requires several times the space occupied by the rest of the machine. It also 5 enables the machine to run at a much greater speed owing to the elimination of the slower running drier and to the general simplification of the machine. By this new 10 method, it is possible to dispense with all agents to moisten the paper. Soft and thinner 15 grades of paper, especially, may be crinkled dry in a satisfactory manner and duplex papers may be crinkled without moisture where the intervening cementitious material has been freshly applied or 20 is in a softened condition. But with heavier, stiffer and more brittle papers, a softening of the fibres by moisture is advisable to prevent them from being broken 25 by the action of the doctor. Only such amount of moisture, if any, need be used as may be found desirable to soften the paper to assist its fibres to adjust themselves without breaking in response to the 30 crinkling action of the doctor, and the expense of drying the crinkled paper may, therefore, be largely reduced or entirely eliminated.

Again, by the use of fluid pressure, in accordance with this invention, widely varying 35 degrees of pressure may be applied to the paper and such pressure may be distributed and regulated as desired and may be varied at will to produce many varieties of crinkling or creasing and to produce various 40 degrees of stretchability in the paper. For example, the fineness, depth and closeness of the crinkles or creases, and their arrangement, may be regulated and designs of various appearance and other effects may be produced in the crinkling.

The invention may be carried out by various forms of mechanism but that shown in the accompanying drawings is preferred.

45 In these drawings, which form part of this specification, and in which like reference numerals designate corresponding parts,

50 Fig. 1 is a side elevation, partly in central section, of a machine for carrying out the invention.

Fig. 2 is a sectional elevation of the perforated crinkling cylinder and its contained parts taken on the line 2—2 of Fig. 1.

55 Fig. 3 is an end elevation, partly in section, showing a modified form of machine for carrying out the invention.

60 Referring to the specific features of the machine shown in Figs. 1 and 2 of the drawings, 1 is a cylinder having its surface provided throughout with perforations of suitable size, shape, relative arrangement and number. Ordinarily perforations of one-sixteenth to one-quarter of an inch in diameter, more or less, and from about ten to

thirty to the square inch, more or less will be sufficient. The cylinder is mounted on a fixed tubular shaft 2. For this purpose the ends of the cylinder 3 and 4 are provided with extensions forming journals 6 and 5, 70 respectively, which surround the shaft 2 outside the cylinder and turn in boxes 8 and 7 carried by the standards 10 and 9, respectively. The tubular shaft 2 is open to the interior of the cylinder through perforations 11. One end of the shaft 2 connects with a pipe 12 and the other end of the shaft is closed by a solid extension 13. 14 and 15 are brackets bolted to the standards 9 and 10, respectively, and having collars 16 80 and 17 through which the ends of the shaft extend and in which the shaft is made fast to prevent it from turning. A spline 18 and a set screw 19 are the means shown in the drawings for holding the shaft fixed in these respective brackets. 20 is a gear fixed on the journal 6 and meshing with a gear 21 for driving the cylinder from any convenient source of power.

Inside the cylinder and surrounding the shaft 2 is a closely fitting tube 22 having a neck 23 forming part of a box 24 of which the outer side toward the periphery of the cylinder is omitted. This box is closed at its ends 25 and 26 and the outer edge of the box fits closely against the inner surface of the periphery of the cylinder. For this purpose, the outer edge of the box is provided with a yielding lip 27 consisting of rubber, felt or other suitable packing designed to provide a substantially air tight fit against the inner surface of the cylinder. In order to hold the box in stationary position on the shaft 2, the tube 22 is provided with set screws 28 and 29, or other suitable means, which pass through the tube and against the shaft 2. By means of these screws the box may be adjusted circumferentially on the shaft 2 and to adjust the box with reference to the working edge of the doctor. The 95 perforations 11 in the shaft 2 register with the neck 23 of the box so that the shaft 2 and its connecting pipe 12 communicate with the interior of the box 24. The pipe 12 connects with an air pump 30 operated by an 100 electric motor 31. A controller 32 controls the speed of the motor and therefore the speed of the pump.

Associated with the cylinder is a doctor 33. It is provided with two arms, such as the arm 34, slidably mounted by means of set screws 36 on collars 37 rotatably mounted on a cross rod 35. This arrangement permits the doctor to be moved to and from the cylinder and to be adjusted circumferentially on the cylinder. 36 is a bent iron presser bar which passes beneath and against the rod 35 and has one end bearing upon the doctor and the other end upon the adjustable support 37. By means of this bar, the 115 120 125 130

pressure of the doctor against the crinkling cylinder 1 may be varied.

38 is a tank in which turns a dampening roll 39. This roll is in contact with two dampening rolls 40 and 41 which bear against the paper 44 on the crinkling cylinder and serve to dampen the paper on this cylinder. 42 and 43 are two adjustable rubber rolls designed to bear against the paper on the cylinder. These rolls have the double function of squeezing surplus moisture, if any, out of the paper and also of pressing the wet or damp paper in close, smooth adherence to and against the cylinder. But a moistening means is not always essential to this invention and may be dispensed with as conditions indicate.

In the operation of the mechanism, as shown in the drawings, the paper 44, taken from a roll 45, passes over the guide roll 46 and thence around the crinkling cylinder 1. It is dampened by dampening rolls 39, 40 and 41, pressed in close adherence to the cylinder 1 by the pressure rolls 42 and 43 and is carried by the cylinder against the doctor, abutment or stripper which provides crinkle or crease forming means acting to strip the paper from the cylinder and form wrinkles therein. Such crinkle forming means may be variously constructed and arranged but is preferably stationary. 47 is the crinkled paper as it comes from the doctor. After the paper has been crinkled, it may be dried in any convenient manner if its condition then requires it.

According to the arrangement shown in Figs. 1 and 2 of the drawings, pressure is applied to hold the paper on the cylinder by sufficiently reducing the air pressure inside the box 24 by means of the exhaust pump 31. This reduces the pressure of the air inside the cylinder in the region of the doctor and, because of the perforations in the cylinder, exhausts or reduces the air pressure on the under surface of the paper and gives an excess pressure of the atmosphere on the outer surface of the paper. The paper is thus held on the cylinder by a positive pressure on its outer surface at and immediately in advance of the operating edge of the doctor and this pressure enables the paper to offer a positive resistance to the stripping action of the doctor. The pressure on the paper may be applied up to the very edge of the doctor or up to a varying distance therefrom according to the relative position of the box 24 and the doctor. This relative position may be varied either by shifting the box on the shaft 2 or by shifting the doctor on the cylinder as provided for by the set screws 56 that engage the arms 34 of the doctor. Furthermore, the pressure on the paper may be readily varied or regulated, as desired, as by varying or regulating the speed of the exhaust pump 31 or its suction.

As a result, the crinkles formed in the paper may be made finer, sharper, closer together and more numerous than it has been possible to attain heretofore, and new effects in the character and appearance of the crinkling or creasing of the paper may be produced as well as varying the degrees of stretchability of such crinkles or creases. These effects may be regulated or varied, as desired, and the effects may be controlled by selecting the proper size and disposition of the perforations in the cylinder 1. In other words, these various effects may be produced in the paper as the same is delivered from the doctor.

It will also be seen that in accordance with this invention, by maintaining a uniform degree of vacuum within the box 24, the roll of paper under treatment on the crinkling cylinder may be held with substantially the same degree of adherence throughout its length and breadth, resulting in a uniformity in the crinkles and in their character, appearance and stretchability as produced at the doctor, that has not heretofore been attainable. Heretofore, there has been a recognized irregularity in the degree of adherence between the paper and the crinkling cylinder in the same roll of paper under treatment, especially in the heavier grades of paper intended for wrapping and packing purposes, and this irregularity has led to an irregularity in the character, stretchability and appearance of the crinkles, as produced at the doctor in the same roll of paper which the present invention obviates.

While it is preferable in carrying out this process to exhaust air from the interior of a perforated crinkling cylinder, and over a restricted area thereof in the region of and immediately in advance of or at the doctor, thereby depending upon atmospheric pressure against the outer surface of the paper to hold it with the required degree of pressure to the crinkling cylinder, the invention is not restricted to the employment of atmospheric pressure for such purpose but contemplates the employment of any suitable means by which pressure may be exerted against the outer surface of the paper to hold it down on the cylinder at or immediately in advance of the operating edge of the doctor, abutment or other crinkle-forming means. For example, steam pressure may be applied to the outer surface of the paper in advance of the doctor, the steam being supplied to a suitable chamber held closely against the outer surface of the crinkling cylinder. Again, air under pressure may be applied to the outer surface of the paper in a similar way to secure the desired adherence of the paper to the cylinder. Where the fluid pressure is applied to the outer side of the paper the cylinder will not, of course, require to be

perforated. If steam is used as thus indicated it may serve to moisten the paper in addition to its other function.

An arrangement for applying fluid pressure to the outer surface of the paper on an imperforate crinkling cylinder is shown in Fig. 3. As there shown, 48 is the crinkling cylinder and 49 is the doctor. 50 and 51 are the dampening rolls for wetting the paper 10 on the cylinder. 52 is a fluid pressure box having a concave open side to fit over the surface of the cylinder and arranged to be held securely in position. The ends of the box should extend beyond the edges of the 15 paper and there contact with the surface of the cylinder and may be provided with packing 53 to make an air-tight fit or one that is sufficiently close. The side edges of the box may be closed by rollers 54 and 55, preferably of metal and arranged to bear against the paper and make an air-tight fit or one that is sufficiently close. The box should be located as close as possible to the doctor when it is desired to apply holding pressure 20 on the paper as close to the working edge of the doctor as possible. As shown in Fig. 3, roller 54 is just sufficiently spaced from the doctor to allow room for the paper to pass between them, and the roller itself applies holding pressure on the paper immediately 25 on the paper as close to the working edge of the doctor as possible. The arrows show the direction of the fluid pressure. The doctor 49 is designed to be adjustable in the same way as the doctor 33 in Fig. 1, and the box 52 is 30 also designed to be adjustable circumferentially on the cylinder. Thus, the pressure on the paper may be applied up to the very edge of the doctor or up to a short distance 35 therefrom. The invention is not limited to any particular means for applying the desired pressure to the paper but includes and contemplates any means useful for the purpose described. The fluid pressure for holding the paper on the crinkling cylinder may 40 be accomplished by means of a fluid pressure chamber of the exhaust type wherein is maintained a pressure less than atmospheric pressure, or it may be accomplished by means of a fluid pressure chamber of the excess pressure type wherein is maintained a 45 pressure in excess of the atmosphere. Furthermore, such fluid pressure chamber may be located either within or without the crinkling cylinder. The invention is not restricted to variations in the character or location of the fluid pressure chamber.

In connection with Fig. 1, it will be seen that the upper side of the box 24 extends slightly beyond the operating edge of the doctor. As a result of this arrangement

fluid pressure is applied to hold the paper on the cylinder immediately in advance of the edge of the doctor and even at its very edge. The doctor, therefore, has at its edge 70 a positive pressure on the paper to overcome in its operation to strip off the paper and crinkle it.

This invention is not restricted in all of its aspects to the use of fluid pressure to positively hold the paper on the crinkling cylinder, or other support for the paper, to resist the action of the doctor. Other means may be employed for this purpose, that will achieve, at least, some of the results set out in the foregoing such, for example, as the 80 roll 54 in Fig. 3.

This invention may be advantageously used in crinkling papers of any weight or character from the thinnest to the heaviest and whether the paper is waxed or otherwise coated or is of single or more thicknesses. Furthermore, the invention may be applied not only to finished paper, as a converting process of such paper, but it may be applied to the unfinished web in a paper 90 making machine with advantageous results. And while the invention is especially useful in operating upon paper, it may be used to operate upon fabrics or sheets of various materials. Almost any sheet material that is sufficiently pliable may be crinkled or creased or operated upon, owing to the very considerable pressure that may be applied thereto and the facility of regulating such pressure. 100

While I have shown and described the invention in the preferred manner of carrying it out, it will be understood that various modifications may be made therein without departing from the scope of the invention. 105

What I claim is:

1. In an apparatus for making crinkled paper, a supporting surface for the paper and crinkle forming means to strip the paper from said surface and thereby crinkle it, in 110 combination with means for applying pressure to the paper immediately in advance of said crinkle forming means to limit the stripping action thereof.

2. In an apparatus for making crinkled paper, a supporting surface for the paper and crinkle forming means to strip the paper from said surface and thereby crinkle it, in 115 combination with means for applying pressure to the paper immediately in advance of said crinkle forming means to limit the stripping action thereof, said means and said crinkle forming means being adjustable relative to each other so as to regulate the distance from the edge of the crinkle forming 120 means at which such pressure is applied.

3. In an apparatus for making crinkled paper, a supporting surface for the paper and crinkle forming means to strip the paper from said surface and thereby crinkle it, in 125

combination with means for applying pressure in varying degrees to the paper immediately in advance of said crinkle forming means to limit the stripping action thereof.

6 4. In an apparatus for making crinkled paper, a supporting surface for the paper and crinkle forming means to strip the paper from said surface and thereby crinkle it, in combination with means for applying pressure to the paper immediately in advance of said crinkle forming means to limit the stripping action thereof, and means to regulate said pressure.

15 5. In an apparatus for making crinkled paper, a supporting surface for the paper and crinkle forming means to strip the paper from said surface and thereby crinkle it, in combination with means acting immediately in advance of said crinkle forming means to 20 limit the stripping action thereof.

25 6. In an apparatus for making crinkled paper, a supporting surface for the paper and crinkle forming means to strip the paper from said surface and thereby crinkle it, in combination with means acting immediately in advance of said crinkle forming means to limit the stripping action thereof, said means and said crinkle forming means being relatively adjustable to and from each other.

30 7. In an apparatus for making crinkled paper, a rotating cylinder for the paper and crinkle forming means to strip the paper from said cylinder and thereby crinkle it, in combination with means for applying pressure to the paper immediately in advance of said crinkle forming means to limit the stripping action thereof.

40 8. In an apparatus for making crinkled paper, a rotating cylinder for the paper and crinkle forming means to strip the paper from said cylinder and thereby crinkle it, in combination with means for applying pressure to the paper immediately in advance of said crinkle forming means to limit the stripping action thereof, said means and said crinkle forming means being adjustable relative to each other so as to regulate the distance from the edge of the crinkle forming means at which such pressure is applied.

45 9. In an apparatus for making crinkled paper, a rotating cylinder for the paper and crinkle forming means to strip the paper from said cylinder and thereby crinkle it, in combination with means for applying pressure to the paper immediately in advance of said crinkle forming means to limit the stripping action thereof, and means to regulate said pressure.

50 10. In an apparatus for making crinkled paper, a rotating cylinder for the paper and crinkle forming means to strip the paper from said cylinder and thereby crinkle it, in combination with means for applying pressure to the paper immediately in advance of said crinkle forming means to limit the strip-

ping action thereof, said means and said crinkle forming means being adjustable relative to each other so as to regulate the distance from the edge of the crinkle forming means at which such pressure is applied, and means to regulate said pressure.

55 11. In an apparatus for making crinkled paper, a supporting surface for the paper and crinkle forming means to strip the paper from the surface and thereby crinkle it, in combination with means for causing the paper to adhere to said surface by fluid pressure.

60 12. In an apparatus for making crinkled paper, a supporting surface for the paper and crinkle forming means to strip the paper from the surface and thereby crinkle it, in combination with means for causing the paper to adhere to said surface by fluid pressure in varying degrees.

65 13. In an apparatus for making crinkled paper, a supporting surface for the paper and crinkle forming means to strip the paper from the surface and thereby crinkle it, in combination with means for causing the paper to adhere to said surface by fluid pressure, the area of pressure and said crinkle forming means being relatively adjustable to and from each other.

70 14. In an apparatus for making crinkled paper, a supporting surface for the paper and crinkle forming means to strip the paper from the surface and thereby crinkle it, in combination with means for causing the paper to adhere to said surface by fluid pressure, and means to regulate said fluid pressure.

75 15. In an apparatus for making crinkled paper, a rotating cylinder for the paper and crinkle forming means to strip the paper from the cylinder and thereby crinkle it, in combination with means for causing the paper to adhere to said cylinder by fluid pressure.

80 16. In an apparatus for making crinkled paper, a rotating cylinder for the paper and crinkle forming means to strip the paper from the cylinder and thereby crinkle it, in combination with means for causing the paper to adhere to said cylinder by fluid pressure, and means to moisten the paper.

85 17. In an apparatus for making crinkled paper, a supporting surface for the paper and crinkle forming means to strip the paper from the surface and thereby crinkle it, in combination with means for causing the paper to adhere to said surface by fluid pressure over a restricted area of said surface.

90 18. In an apparatus for making crinkled paper, a rotating cylinder for the paper and crinkle forming means to strip the paper from the cylinder and thereby crinkle it, in combination with means for causing the paper to adhere to the cylinder by fluid

pressure over a restricted area of said surface.

19. In an apparatus of the character described, a perforated supporting surface for the sheet to be operated upon in combination with crinkle forming means to strip the sheet from said surface and thereby form crinkles or creases in the sheet, and means for reducing the air pressure on the underside of said surface.

20. In an apparatus for making crinkled paper, a perforated supporting surface for the paper in combination with means for reducing the air pressure on the underside of said surface, and crinkle forming means to strip the paper from said surface and thereby crinkle it.

21. In an apparatus of the character described, a rotating suction cylinder to support the sheet to be operated upon combined with crinkle forming means to strip the sheet from said cylinder and thereby form crinkles or creases in the sheet.

22. In an apparatus for making crinkled paper, a rotating cylinder having a perforated supporting surface for the paper in combination with crinkle forming means to strip the paper from said surface and thereby crinkle it, and means for causing the paper to adhere to said cylinder by fluid pressure.

23. In an apparatus for making crinkled paper, a rotating cylinder having a perforated supporting surface for the paper in combination with means for reducing the air pressure on the underside of said surface, and crinkle forming means to strip the paper from said surface and thereby crinkle it.

24. In an apparatus for making crinkled paper, a rotating cylinder having a perforated supporting surface for the paper in combination with means for reducing the air pressure over a restricted area of the underside of said surface, and crinkle forming means to strip the paper from said surface and thereby crinkle it.

25. In an apparatus for making crinkled paper, a perforated supporting surface for the paper in combination with means for variably reducing the air pressure on the underside of said surface, and crinkle forming means to strip the paper from said surface and thereby crinkle it.

26. In an apparatus for making crinkled paper, a rotating cylinder having a perforated supporting surface for the paper in combination with means for variably reducing the air pressure over a restricted area of the underside of said surface, and crinkle forming means to strip the paper from said surface and thereby crinkle it.

27. In an apparatus for making crinkled paper, a rotating cylinder having a perforated supporting surface for the paper in combination with means for variably reduc-

ing the air pressure over a restricted area of the underside of said surface, and crinkle forming means to strip the paper from said surface and thereby crinkle it.

28. In an apparatus for making crinkled paper, a rotating cylinder having a perforated supporting surface for the paper in combination with crinkle forming means an exhaust pipe communicating with the interior of said cylinder and an exhaust pump associated with said pipe.

29. In an apparatus for making crinkled paper, a rotating cylinder having a perforated supporting surface for the paper in combination with crinkle forming means an exhaust pipe communicating with the interior of said cylinder and an exhaust pump associated with said pipe, and means to vary the power of said pump.

30. In an apparatus for making crinkled paper, a rotating cylinder having a perforated supporting surface for the paper in combination with crinkle forming means an exhaust pipe communicating with a restricted area of the underside of said surface, and an exhaust pump associated with said pipe.

31. In an apparatus for making crinkled paper, a rotating cylinder having a perforated supporting surface for the paper in combination with crinkle forming means an exhaust pipe communicating with a restricted area of the underside of said surface, and an exhaust pump associated with said pipe, and means to vary the power of said pump.

32. In an apparatus for making crinkled paper, a rotating cylinder having a perforated supporting surface for the paper in combination with means for reducing the air pressure on the underside of said surface, crinkle forming means to strip the paper from said surface and thereby crinkle it, and means to moisten the paper.

33. In an apparatus for making crinkled paper, a rotating cylinder having a perforated supporting surface for the paper in combination with means for reducing the air pressure over a restricted area of the underside of said surface, crinkle forming means to strip the paper from said surface and thereby crinkle it, and means to moisten the paper.

34. In an apparatus for making crinkled paper, a rotating cylinder having a perforated supporting surface for the paper in combination with crinkle forming means a chamber located inside said cylinder and fitting over a restricted area thereof, a tubular shaft for the cylinder communicating with said chamber, and exhaust means associated with said shaft to exhaust air from the chamber.

35. In an apparatus for making crinkled paper, a rotating cylinder having a perforated supporting surface for the paper in

combination with crinkle forming means a circumferentially adjustable chamber located inside said cylinder and fitting over a restricted area thereof, and exhaust means 5 communicating with said chamber.

36. In an apparatus for making crinkled paper, a rotating cylinder having a perforated supporting surface for the paper in combination with crinkle forming means a 10 circumferentially adjustable chamber located inside said cylinder and fitting over a restricted area thereof, a tubular shaft for the cylinder communicating with said chamber, exhaust means associated with said 15 shaft to exhaust air from the chamber, and provisions to regulate said exhaust means.

37. In an apparatus for making crinkled paper, a rotating cylinder having a perforated supporting surface for the paper in 20 combination with a chamber located inside said cylinder and fitting over a restricted area thereof, a tubular shaft for the cylinder communicating with said chamber, exhaust means associated with said shaft to 25 exhaust air from the chamber, and a circumferentially adjustable abutment to strip the paper from the cylinder and thereby crinkle it.

38. The process of making a crinkled sheet 30 which consists in causing the sheet to adhere to a supporting surface by fluid pressure and stripping the sheet from said supporting surface by a suitable crinkle forming means.

35. 39. The process of making crinkled paper which consists in causing paper to adhere to the surface of a rotating cylinder by fluid pressure and stripping the paper from said cylinder by a suitable stationary crinkle 40 forming means.

40. The process of making crinkled paper having varying degrees of stretchability which consists in causing paper to adhere to a supporting surface by varying degrees 45 of fluid pressure and stripping the paper from said supporting surface by a suitable crinkle forming means.

41. The process of making crinkled paper 50 which consists in causing paper to adhere to a supporting surface by fluid pressure regulated in accordance with the character of crinkling desired in the finished product and stripping the paper from said supporting surface by a suitable crinkle forming means.

55. 42. The process of making crinkled paper which consists in depositing paper upon a 60 perforated supporting surface, reducing the air pressure on the underside of said surface and stripping the paper from said surface by a suitable crinkle forming means.

60. 43. The process of making crinkled paper which consists in depositing paper upon a 65 perforating supporting surface, reducing the air pressure on the underside of said surface

proportioned to the degree of stretchability desired in the finished product and stripping the paper from said surface by a suitable crinkle forming means.

44. The process of making crinkled paper 70 which consists in causing paper to adhere to the surface of a rotating cylinder by fluid pressure regulated in accordance with the character of crinkling desired in the finished product and stripping the paper from said cylinder by a suitable stationary abutment.

45. The process of making crinkled paper 75 which consists in depositing paper upon a perforated supporting surface, reducing the air pressure over a restricted area on the underside of said surface and stripping the paper from said surface by a suitable crinkle forming means.

46. The process of making crinkled paper 80 which consists in depositing paper upon a perforated supporting surface, reducing the air pressure over a restricted area on the underside of said surface, said air pressure being regulated in accordance with the character of crinkling desired in the finished product and stripping the paper from said surface by a suitable crinkle forming means.

47. The process of making crinkled paper 85 which consists in depositing paper on a supporting surface, stripping the paper from said surface by a suitable crinkle forming means, and applying pressure to the paper immediately in advance of said crinkle forming means to limit the stripping action 90 thereof.

48. The process of making crinkled paper 95 which consists in depositing paper on a rotating cylinder, stripping the paper from said cylinder by a suitable crinkle forming means, and applying pressure to the paper immediately in advance of said crinkle forming means to limit the stripping action 100 thereof.

49. The process of making crinkled paper 110 which consists in depositing paper on a rotating cylinder, stripping the paper from said cylinder by a suitable crinkle forming means, and applying fluid pressure to the paper immediately in advance of said crinkle forming means to limit the stripping action 115 thereof.

50. Paper creping apparatus comprising a 120 supporting surface to which the paper is adapted to adhere and equipped with means for causing close adherence of the paper thereto by suction, and crinkle forming means against which the paper engages to clear the same from said surface and produce a crepe effect therein.

51. Apparatus for making stretchable 125 paper, comprising a rotatable drum having a suction box associated therewith and operative upon the surface thereof, and crinkle forming means co-operative with said drum, said drum, suction box and crinkle- 130

- 57 forming means having a construction and relative arrangement for crinkling the paper web.
52. The herein described method of crinkling paper which consists in holding paper to a crinkling drum by air suction exerted upon a predetermined area of said drum, and in adjusting a clearer member associated with such drum with reference to such suction area to produce variable crinkling in the paper. 60
53. In an apparatus for making crinkled paper, means for wetting the paper, a supporting surface for the wet paper and crinkle forming means to strip the wet paper from said surface and thereby crinkle it, in combination with means for applying pressure to the paper immediately in advance of the operating edge of said crinkle forming means to limit the stripping action thereof. 65
54. In an apparatus for making crinkled paper, means for wetting the paper, a supporting surface for the wet paper and crinkle forming means to strip the wet paper from said surface and thereby crinkle it, in combination with means acting immediately in advance of the operating edge of said crinkle forming means to limit the stripping action thereof. 70
55. In an apparatus for making crinkled paper, means for wetting the paper, a rotating cylinder for the wet paper and crinkle forming means to strip the wet paper from said cylinder and thereby crinkle it, in combination with means for applying pressure to the paper immediately in advance of the operating edge of said crinkle forming means to limit the stripping action thereof, and means to regulate said pressure. 75
56. The process of making crinkled paper which consists in depositing wet paper on a supporting surface, stripping the wet paper from said surface by a suitable crinkle forming means, and applying pressure to the paper immediately in advance of said crinkle forming means to limit the stripping action thereof. 80
57. The process of making crinkled paper which consists in depositing wet paper on a rotating cylinder, stripping the wet paper from said cylinder by a suitable crinkle forming means, and applying pressure to the paper immediately in advance of said abutment to limit the stripping action thereof. 85
58. The process of making crinkled paper in the web which consists in leading a web of paper from a supply roll, suitably wetting the paper and depositing it upon a supporting surface, stripping the wet paper from said surface by a suitable crinkle forming means, and applying pressure to the paper immediately in advance of said crinkle forming means to limit the stripping action thereof. 90
59. In an apparatus for making crinkled paper in the web, a supporting surface for the paper and a crinkle forming means to strip the paper from said surface and thereby crinkle it, in combination with means for applying pressure to the paper immediately in advance of said crinkle forming means to limit the stripping action thereof, said means and said crinkle forming means being adjustable relative to each other so as to regulate the distance from the edge of the crinkle-forming means at which such pressure is applied. 95
60. In an apparatus for making crinkled paper, a supporting surface for the paper, means for causing adherence of the paper to such supporting surface whereby it is caused to move the paper thereon forward and an abutment to strip the paper from said surface and thereby crinkle it, in combination with means for applying fluid pressure to the paper immediately in advance of the operating edge of said abutment. 100
61. In an apparatus for making crinkled paper, a supporting surface for the paper, means for causing adherence of the paper to such supporting surface whereby it is caused to move the paper thereon forward and an abutment to strip the paper from said surface and thereby crinkle it, in combination with means acting immediately in advance of the abutment to limit the stripping action thereof. 105
62. The process of making crinkled paper which consists in depositing paper on a supporting surface, conditioning the paper to cause it to adhere to such supporting surface, stripping the paper from said surface by a suitable abutment, and applying fluid pressure to the paper immediately in advance of said abutment. 110
63. The process of making crinkled paper which consists in depositing paper on a rotating cylinder and stripping the paper from said cylinder by a suitable abutment, and sucking the air from between the paper and cylinder.

This specification signed this 17th day of December, 1918.

NICHOLAS M. GOODLETT.
